DISPENSING ATTACHMENT FOR CANS

Scott M. Abbott, Chicago, Ill., assignor to Crane Packing Company, Chicago, Ill., a corporation of Illinois

Application July 16, 1934, Serial No. 735,508

14 Claims. (Cl. 221—23)

My invention relates to improvements in dispensing attachment for cans.

At present some little difficulty and inconvenience are experienced in the use of five gallon cans and in smaller sized cans in which lubricating oil is commonly sold. It is difficult to pour such oil into the crank case opening of automobile engines as the can cannot be lowered sufficiently to bring the spout at the upper end thereof low enough to insure pouring the oil into said opening without spilling it. The same difficulty occurs to a greater or less extent in the use of cans or containers used for various other liquids even where it is possible to hold 10 the spout of the can close to the receptacle into which the liquid is being poured. This is true particularly where the can and its contents are heavy. Also, in the case of cans which contain 15 maple syrup or other sticky substance of considerable viscosity the liquid is apt to drip from the outlet, necessitating a cleaning of the can in order to handle it conveniently during subsequent operations. Various attempts have been 20 made heretofore to overcome this difficulty by attaching an outlet or spout to the container after it had been filled with the liquid. However, it has been difficult to apply these devices to the can in such a way as to insure a tight joint and 25 also to provide a device which may be removed from the receptacle after it is empty and which 30 may be used again. As a result, the theoretical advantages of an attachment of this character have not been fully attained in actual practice.

The general object of my invention is to provide 35 an improved device of this character having a pointed end which is pushed through the wall of the container and having means whereby said wall may be firmly clamped between shoulders on said device to hold the latter securely in place 40 and prevent leakage.

A contributory object is to provide an attachment of this character having means for expanding the inner part of the attachment, after 45 it has been pushed through the opening formed by the pointed inner end, thus forming a positive abutment against which the can wall may be clamped from the outside.

Other objects are: to provide a device of this 50 character which does not require the turning of the portion which is forced through the can wall in order to effect the clamping engagement; to provide a device in the form of a spigot, having an improved valve in the outer end; to provide a device having an adjustable inner portion 55 which may be expanded and contracted from

the outer portion; to provide a device which may be successfully used by an inexperienced person, and to provide a device which may be withdrawn from the can on which it has been used, without damaging it, after the can is empty, and 5 may be reused on other cans for an indefinite period.

The device as shown in the accompanying drawing illustrates a commercial embodiment of the invention and certain minor modifications 10 thereof. In said drawing:

Fig. 1 is a side elevation of a rectangular can with the dispensing attachment in the form of a spigot applied thereto;

Fig. 2 is an enlarged side elevation of the 15 spigot;

Fig. 3 is a top view thereof partly in section;

Fig. 4 is a central sectional elevation;

Fig. 5 is a perspective view of certain details;

Fig. 6 is a plan view of a modified spigot on a 20 smaller scale applied to a cylindrical can; and

Fig. 7 is an elevation on a small scale of a 25 spigot having a flexible tube or extension.

The can 10 is intended to be typical of any 30 rectangular can, i. e., one having flat vertical walls, with the usual handle 11 at the top and a spout 12 closed by a suitable cap.

The body of the dispensing attachment or spigot 13 is of generally cylindrical form, the tubular outer part having a flange or shoulder 14 and a reduced cylindrical extension 15 with a gasket or compressible washer 16 against the shoulder 14. This gasket may be made of oil proof rubber, cork or other material suitable for the liquid, the escape of which is 35 intended to be prevented by this sealing member. The cylindrical extension 15 has transverse openings 17 therethrough, through which the liquid enters in flowing through the tubular member 13. The inner end of the cylindrical 40 extension 15 has a tapered or cone shaped portion 18 which acts as a cam surface as herein-after described.

The conical end 18 has a non-circular opening in it, i. e. square, hexagonal or of other 45 outline, preferably square, to receive the shaft 19 of square cross section, which slides back and forth in said opening without rotating. The inner end of the shaft 19 carries a cylindrical part 20 which has a conical head 21 tapering 50 to a sharp point. Surrounding the shaft 19 are a plurality of curved shells which conjointly present a cylindrical outline no larger in cross section than the cylindrical end 20. In the present case there are two such shells or wings 55

22, 23, which, in effect are pivoted at their inner ends near the head 20 and which may be swung outwardly at their outer ends to increase the effective diameter of the body and to present positive abutments so that the wall of the container 10 may be clamped between these adjustable shells or abutments and the fixed abutment 14, preferably with the interposed, thick, compressible gasket 16.

10 These adjustable abutments are each in the form of a half cylinder, as shown in Fig. 5. The longer one 22 has a ring 24 at its inner end loosely surrounding the square shaft 19 whereby it may swing to a certain angle without binding, the opening in said ring being rectangular and preferably oblong, with two of the walls at an incline, as shown in Fig. 4. In like manner the half cylinder 23 also has a ring 25 at its inner end, surrounding said square shaft 19 but of smaller diameter than the ring 24, as shown in Figs. 4 and 5, the opening in said ring being oblong in this case also, with two inclined walls. The surface or corner of the ring 25 adjacent the ring 24 is beveled or rounded somewhat and the corresponding corner of the ring 24 is also rounded, to facilitate the swinging or rocking movement of the two abutments to the position shown in Fig. 4 with their outer ends spread apart and to insure their return movement. The rings are normally at right angles to the shaft 19 and the semi-cylindrical abutments 22, 23 are at right angles to said rings and hence parallel to said shaft. A helical spring 26 is confined between the ring 25 and the conical end 18 and holds the two shells 22, 23 normally in contact with each other, and parallel to said shaft, by pressing the two rings against the flat surface of the head 20.

40 The outer end 27 of the shaft 19 is threaded with a fine thread, and is received within a screw threaded cone shaped head or nut 28 spaced from but secured to an annular projection 29 on the valve 30 by means of brackets preferably formed integral therewith. The valve housing 30 may be gripped in the hand as a handle and rotated with reference to the cylindrical body 13, the part 29 fitting within and rotating in the cylindrical body 13, and the flange 31 serving as a stop to resist the inward thrust of the shaft 50 under the influence of the helical spring 26. The nut 28 rotates with the valve housing and draws in the square shaft 19, against the action of said helical spring, thus forcing the outer ends of the pivoted abutments 22 and 23 against the conical surface 18. The latter acts as a cam and spreads the abutments sufficiently to enable them to slide over the cylindrical extension 15 and press the wall 10 of the cam against the gasket 16 and the shoulder 14, thus clamping said wall between positive abutments and forming a tight seal. If the valve housing 30 is rotated in the opposite direction, the square shaft 55 19 is moved to the rear under the action of the spring 26, and thus the pivoted abutments are 60 swung down to the position shown in Figs. 2 and 3 by the pressure of the end of the helical spring against the end rings 24, 25, in which initial position they form substantially a complete cylinder of a diameter no greater than and preferably less than the diameter of the cylindrical extension 15.

70 The valve housing 30 is equipped with any suitable valve handle 32 above the same, said handle being fastened by a pin 33 to the valve stem 34, the lower part of which flares as a cone

shaped valve 35 with one side cut out, whereby rotation of said valve opens or cuts off communication between the interior of the hollow body 13 and the nozzle 36. The spring 37 is compressed between the lower surface 38 of the handle and the shoulder 39 in the valve housing, thus exerting an upward pressure on the tapering valve and tending to hold it in place, thus preventing leakage without the use of packing or gaskets.

10 In view of the foregoing description, the manner of applying the device to the can and the operation of the spigot will be evident. The can 10 is placed on its side so that the wall to which the dispensing attachment is to be applied, is uppermost. The sharp end is then forced through the metal and the device pushed in until further movement is limited by the shoulder 14 and gasket 16, after which the valve housing 30 is used as a handle and rotated to expand the two inner abutments and clamp the device firmly in place. 15 If it is necessary to prevent rotation of the device as a whole, the body 13 may be held against turning by the other hand. Also, if after screwing the device up hard to insure against leakage, the valve should not be in vertical position, right side 20 up, the parts may be unscrewed a little to relax the pressure and the device as a whole rotated by turning the body 13 the necessary amount, after which the retightening of the parts will bring the valve to vertical position. However, the 25 thread 27 being a fine thread, and the gasket 16 being comparatively thick, the latter may be compressed enough to bring the valve to the desired position and make a tight joint merely by screwing the parts a little tighter and without making 30 any adjustment whatever.

Where the device is to be applied to a cylindrical can as distinguished from one having flat walls, the flange 14 instead of presenting a flat inner face may be curved as shown at 40 in Fig. 6, 40 although in most cases such curved flange is not necessary as a flat flange and the proper gasket will insure a tight seal, even on a cylindrical can.

Where a flexible extension is desired to afford a little more latitude in discharging the contents 45 of the container, a spigot may be formed with an extension in the form of a flexible hose or cable 41 which may be an armored cable or otherwise. This short length of flexible tubing may be merely in the form of an attachment to slip 50 over the nozzle 36.

I claim:

1. A dispensing attachment comprising a hollow body having a sharp inner end whereby said body may be pushed part way into a container when said sharp end is forced through the wall of said container, a movable abutment associated with the portion of said body which penetrates said wall and means on the outer portion of said body for moving said abutment away 60 from and toward the longitudinal axis of said body, independently of the inward movement of said body through said wall, and after the completion of said movement.

2. A detachable spigot for containers comprising 65 an elongated hollow body, a tapering end to penetrate a wall of said container, inner clamping members mounted on said body and normally located within the cross sectional outline of said end, to pass through the opening made thereby, 70 said members being movable outwardly relatively to each other, and means on the outer end of said body to move said members outwardly beyond the limits of said cross sectional outline and to retract them.

3. An attachment spigot for containers comprising a hollow cylindrical body having a pointed inner end to penetrate a wall of said container, a pair of movable members mounted on opposite sides of said body and normally having a cylindrical outer surface of a diameter no greater than that of the portion of said body which protrudes into said container and an actuating member movable longitudinally within said body, one end of which is connected to said movable members to swing them outwardly, and rotatable means at the other end of said body to move said actuating member.

4. An attachment spigot for containers comprising a hollow body having a pointed inner end to penetrate a wall of said container, a pair of movable members mounted on opposite sides of said body and normally having a cross sectional outline, including the outline of said body, no greater than that of the opening in said wall made by the penetration of said pointed end, an actuating member movable longitudinally within said body, one end of which is connected to said movable members to swing them outwardly, and manually operable means at the other end of said body to move said actuating member.

5. An attachable and detachable spigot for containers, comprising an elongated body having a sharp inner end to puncture a wall of said container, abutments movably mounted on said body whereby they may expand and contract, resilient means normally holding said abutments in contracted position, whereby they do not interfere with the insertion or withdrawal of said body through said punctured wall, and means near the outer end of said body having mechanical connections with said movable abutments, whereby the latter may be expanded against the action of said resilient means and permitted to be retracted thereby.

6. An attachable and detachable spigot for containers, comprising a hollow, elongated body having a sharp inner end to puncture a wall of said container, members movably mounted on said body whereby they may expand to form inner abutments or may contract so as not to interfere with the insertion or withdrawal of said body through said punctured wall, resilient means normally holding said members in contracted position, positively actuated means near the outer end of said hollow body having mechanical connections through the same to said inner abutments, whereby the latter may be expanded against the action of said resilient means and permitted to be contracted thereby, and an outer abutment on said body, between said means and said movable inner abutments, whereby said container wall surrounding said aperture may be clamped between said outer and inner abutments.

7. An attachment spigot for thin walled liquid containers comprising an elongated body, a rod passing longitudinally therethrough and non-rotatable with respect to the same, the outer end of said rod being screw threaded, a valve at the outer end of said body having a nut engaging said screw threaded rod whereby rotation of said valve will move said rod longitudinally, a plurality of pivoted members mounted on the inner end of said body and actuated by said rod and a sharp inner end on said body to penetrate the container wall.

8. An attachment spigot comprising a body portion having a pointed inner end to puncture a container wall, a flange to engage the outer surface of said container wall, inclined surfaces on

said body portion between said inner end and said flange, and adapted to extend within said container beyond said punctured wall on the side opposite said flange, a pair of abutments pivoted to said body inwardly of said inclined surfaces, and a longitudinally movable shaft passing through said body for drawing said abutments against said inclined surfaces to spread the same and force them into positive engagement with the inner surface of said wall.

9. An attachment spigot for containers comprising an elongated, hollow body having a reduced inner extension, a shoulder thereon, said extension having a conical inner surface, a rod passing longitudinally through said body, a pair of wings pivoted to said rod at a point remote from said conical surface, the outer ends of said wings being normally adjacent said conical surface and means for moving said rod outwardly to cause the outer ends of said wings to ride over said conical surface and spread the same.

10. An attachment spigot for liquid containers comprising a shaft, a pair of semi-circular wings surrounding the same, each wing having a ring at its inner end with an opening through which said shaft passes loosely in non-rotatable engagement, an outer tubular member, for conveying liquid from said container, surrounding the outer end of said shaft, a cam surface on the inner end of said tubular member adjacent the outer ends of said wings, and means near the outer end of said tubular member for drawing said shaft outwardly to cause said cam surface to be engaged by and to spread said wings.

11. An attachment spigot for liquid containers comprising a tubular casing having a flange intermediate its ends, a transverse opening through said casing on one side of said flange, a closure for the adjacent end of said tubular casing having an axial opening therein, a shaft passing longitudinally through said casing and through said axial opening, a faucet having an extension fitting within the other end of said casing and having a nut spaced therefrom by brackets, the outer end of said shaft having screw threaded engagement with said nut, semi-cylindrical wings each having a ring at the end thereof through which the inner end of said shaft slides, and a helical spring between said rings and the inner end of said tubular casing.

12. An attachment spigot for liquid containers comprising a tubular casing having a flange intermediate its ends, the inner end of said casing having a tapering closure with a rectangular opening therein, a rectangular shaft passing through said opening and positioned axially with respect to said casing, the outer end of said shaft being screw threaded, a head affixed to the inner end of said shaft, a pair of rings on said shaft against said head, an axial extension on each ring normally terminating at said tapering closure, a helical spring between said rings and said closure normally holding said axial extensions parallel to said shaft, a handle at the outer end of said tubular casing and a nut carried thereby engaging the screw threaded end of said shaft, whereby when said handle is rotated said axial extensions are caused to diverge by said tapering closure.

13. A device as in claim 12 wherein the handle is a faucet communicating with said tubular casing to discharge liquid from said container.

14. An attachment spigot for liquid containers comprising a tubular casing having a flange intermediate its ends, the inner end of said casing having a tapering closure with a rectangular

opening therein, a rectangular shaft passing through said opening and positioned axially with respect to said casing, a head affixed to the inner end of said shaft, a plurality of arms pivotally mounted near said head and normally arranged adjacent said shaft with their outer ends near said tapering closure, the outer end of said shaft having a fine screw thread thereon, a faucet at

the outer end of said tubular casing, a nut carried thereby engaging said screw thread, whereby when said faucet is rotated said pivoted arms are caused to diverge by said tapering closure, and a thick compressible gasket positioned inside said flange to permit rotation of said faucet to vertical position. 5

SCOTT M. ABBOTT.
